**METHOD OF RELIEVING PAIN IN CANCER BY
INJECTING LYSOZYME FREE OF PROTEIN-
ACEOUS IMPURITIES**

Enea Giuseppe Scolari, Florence, Italy, assignor to Societa
Prodotti Antibiotici, Milan, Italy
No Drawing. Filed Apr. 2, 1962, Ser. No. 184,597
10 Claims. (Cl. 167—65)

The present invention relates to a method of treating cancer so as to relieve the pain thereof, and more particularly to the use of an agent which is effective as an analgesic in relieving the pain of patients suffering from cancer.

The pain and suffering of patients affected with carcinoma of all different types is of course well known, and it is also well known that in the terminal stage of such carcinoma the patient can no longer obtain relief by the use of the known analgesics and narcotics. As a matter of fact, such patients become dehydrated and undernourished due to the intolerable and persistent pains which prevent them from sleeping, eating or drinking. In terminal stages of such carcinomas the patients even become addicted to narcotics, without obtaining any pain relief therefrom.

It is accordingly a primary object of the present invention to provide a new agent which is effective in the relief of pain of patients suffering from cancer.

It is another object of the present invention to provide a non-narcotic, non-habit forming agent which acts as an effective analgesic in the relief of the pain of patients affected by carcinoma.

It is yet another object of the present invention to provide a method of producing the pain relieving agent of the present invention in a form in which the same can be administered, without side effect, for the relief of pain of a patient affected by carcinoma.

Other objects and advantages of the present invention will be apparent from a further reading of the specification and of the appended claims.

With the above and other objects in view, the present invention mainly comprises as a method of relieving the pain of a patient suffering from cancer the injection of such patient with lysozyme.

Lysozyme is a basic polypeptide of enzymatic nature, positively charged, discovered by Fleming in 1922. It is present in blood, tissues and excretions such as tears, and in women's milk. In higher concentrations it occurs in brain and adrenals. Lysozyme is known to have a high degree antibacterial properties, and to build a physiological defense mechanism which acts as a true natural protection against bacterial and viral invasions.

In accordance with this invention it has been discovered that the injection of patients suffering from cancer, either intravenously or intramuscularly, brings about a high degree of relief of the pain, and in many cases a complete and total disappearance of pain. This relief of pain has been achieved in cases which could no longer benefit by the use of known analgesics and narcotics, i.e. patients who could no longer obtain relief by the use of their analgesic or narcotic treatment were given relief by the use of lysozyme in accordance with the present invention.

While the administration of lysozyme in accordance with the present invention cannot in any way cure or even reduce the carcinoma, it does bring a long lasting relief to the patient suffering from the carcinoma so as to at least give such patient a ray of hope and ease the suffering of the patient.

In its pure form lysozyme is an impalpable white powder, of sweetish taste. Its structure has been studied by numerous workers, and recently J. Jolles and P. Jolles have published a note concerning the complete developed

2

formula of egg white lysozyme (Comptes Rendus des Seances de l'Accademie des Sciences, vol. 253, pages 2773-75, Seance of December 4, 1961).

Aqueous lysozyme solutions, when sterile, indefinitely maintaining their chemical-physical and pharmacobiological characteristics. However, lysozyme in its normal form if used for the preparation of solutions for parenteral administration can cause disagreeable secondary phenomena. It is therefore still another object of the present invention to provide a method of purifying lysozyme so as to make the same suitable for parenteral administration without any danger of secondary side effects.

In accordance with the present invention it is possible to prepare ampoules of lysozyme for intramuscular or intravenous injection. It is also possible to prepare lysozyme in lyophilized form for dissolution in a retard-solvent solution, such as an aqueous polyvinylpyrrolidone solution, for intramuscular or intravenous administration with the retard-solvent slowing the effect of the lysozyme and thereby giving it a more prolonged action.

Lysozyme was administered to numerous patients suffering from cancer of various localizations in advanced stage of evolution, with numerous metastases, in accordance with the present invention, the patients no longer being surgically or radiologically recoverable, and suffering terribly with persistent and intermittent pains which were refractory to every other therapy. Among the various conditions from which the patients were suffering were epithelial cancers of the oral cavity, lips and cheek mucosa, cheeks, alveolar fornice, oral floor and palate, tonsils, and tongue. The great majority showed necrosis and ulcerations, and all but one had lymph glands metastases in the suprathyroid, milohyoid and jugular regions. In one case only lymph glands metastases were present in the sub-mandibular and latero-cervical regions, deriving from an epithelioma of the tongue, which was clinically healed under radium-therapy. In two of the patients there were also radiologically verified metastases, respectively in the cervical and lumbar segment of the vertebral column.

There were also cases of endopelvic tumors, originating from the prostate, the recto-vaginal septum the uterus itself, with invasive growth into the parametria or/and into the vagina. In the two latter cases and in the case of the prostatic tumor metastases in the cervical, lumbar and sacral segments of the vertebral column were present. Also one case of epithelioma of the left maxillary and ethmoidal sinuses and one case of spinocellular epithelioma of the skin of the face, with diffuse regional metastases in the lymph glands. In addition, a very serious case in preagonic conditions, a woman, operated 2 years before for mammary carcinoma, who suffered presently from numerous vertebral metastases in the cervical and lumbosacral segments of the column. Also treated was a case of gastric cancer.

All the above mentioned patients were selected from cases that could not benefit any more by surgical or radio-logical treatment; they had all severe pains, either continuous or subcontinuous, with attacks of tormenting exacerbations at various frequencies. Most of these patients were obliged to lay motionless in bed in coapted position; they were underfed and almost continuously sleepless; some of them were already in precachectic conditions. In a few cases, only the pains were supportable and intermittent or of a dull type. The irradiations of the pains were the customary ones for the single localizations. The patients with the most severe pains had been previously submitted to analgesic treatment, with morphine and morphinan derivatives or meperidine, suffering therefore of the connected intoxications; all other patients were treated with minor analgesics or complementary drugs, as barbiturates, antipyretic analgesics, bromo derivatives, gang-

lion-blocking agents and so on. Lysozyme therapy was adopted after discontinuance of all other analgesic treatments; only therapeutic integrations as analectics, infusions and other not analgesic means were eventually used.

Lysozyme was administered by intramuscular injection, first at doses of 75 mg. twice or three times daily and in the most resistant cases at doses of 125-250 mg. twice daily. Lyophilized preparations or preparations in a retarding solvent (polyvinylpyrrolidone) were used. With 20 cases treated the obtained results are briefly as follows: in 14 cases a progressive diminution of pains up to complete or nearly complete disappearance; in 4 cases a remarkable reduction of pains with restoration of the possibility of eating, resting overnight, getting up and moving (in any case a far improved condition than that previously obtained with opiates or their derivatives); in 2 cases a very slight amelioration or no amelioration at all.

An isolated attack of pain was sometimes recorded, even in favorable cases. However these attacks were far less severe than those which afflicted the patients before the beginning of treatment and of a shorter duration. The amelioration lasted even after discontinuance of lysozyme treatment, eventually with the subsidiary use of harmless analgesic drugs.

In another 30 cases only intravenous injections were used. Lysozyme treatment was started after previous suspension of every other antalgic therapy. The lysozyme average posology, by intramuscular administration in the cases previously mentioned was 125 mg. or 150 mg. doses (lyophilized lysozyme or lysozyme in a retard-solvent solution of polyvinylpyrrolidone) twice a day, during a period of 20-25 days.

In the more refractory cases it was necessary to apply to 2 daily injections of 250 mg. lysozyme. The average posology, intravenously in the 30 cases herein discussed was of a daily injection of 250 mg. during a period of 20-25 days.

Out of 20 cases treated with lysozyme intramuscularly there was obtained the following results:

Total or almost total disappearance of pain in 14 cases; a satisfactory suffering decrease in 2 cases, and no effect in the other two cases.

Out of 30 cancerous patients affected by the so called refractory pains, in 20 cases, there was obtained by endovenous lysozyme administration total disappearance of algic symptomatology; lysozyme antalgic action was partial in 7, and no effect in 3 cases. The percentage of positive results (total and partial disappearance of suffering) is 90%.

The best and most rapid results were reached by endovenous administrations; within the first 24-36 hours of treatment an improvement in pain symptomatology was already evident; in the less favorable cases it was necessary to wait until the third to fifth day. Intramuscular administration has a more gradual effect (within 3-7 days) and positive results are reached only after 10-15 days of treatment.

A certain number of the cases treated by lysozyme endovenous administration, concerns a group of patients previously submitted to a lysozyme intramuscular treatment. When, owing to a continued worsening of the neoplastic process and the reappearance of painful symptomatology by the renewal of the same treatment appeared inefficient, a satisfactory renewed sensibility to the therapy was obtained by using endovenous administration.

In still another 10 cases further treated with intramuscular lysozyme administrations, concordant results were obtained. Based on these sufficiently regular results, the following scheme of standard therapy may be applied:

(1) Immediate suspension of every other antalgic treatment.

(2) Initial therapy may be of a sole daily dosage of 250 mg. lysozyme intravenously. In case of a retarded effect, after 3-5 days, redouble the dose and administer

it every day, endovenously, all at a time or fractionated, with an interval of 12 hours. (Lyophilized lysozyme, also in solution, at room temperature maintains unaltered for a long time.)

(3) When analgesic action appears stable for at least 20-25 days, it is possible to try to reduce the doses to one-half, eventually using intramuscular treatment. In positive cases, after 2-3 weeks, a maintaining therapy with a minimum dose of 75 mg., once or twice a day may be tried. In fully favorable cases, treatment can be suspended, eventually resorting to collateral drugs, with a tranquilizing, antistaminic and antispastic action.

(4) When painful symptomatology reappears (generally 25-40 days after treatment suspension) a new therapy cycle is required.

The above-mentioned therapeutic schema, can be naturally modified according to the most various particular circumstances.

It is clear from the treatments carried out using the lysozyme treatment in accordance with the present invention that the lysozyme is effective to reduce pain in all types of cancer, and is not selectively effective in only one or another type of cancer.

As indicated above it is another object of the present invention to provide a method of producing lysozyme which can be used for injection purposes without the danger of undesired side effects.

With this object in view, the present invention mainly comprises the heating of an aqueous 2-10% lysozyme solution containing undesired secondary proteins to a temperature sufficiently high to denature the secondary proteins, cooling the thus treated solution so as to cause precipitation of the thus denatured secondary proteins, and filtering the thus cooled solution so as to separate the denatured proteins therefrom, thereby obtaining a lysozyme solution which can be used for injection purposes.

The heating of the lysozyme solution is preferably carried out at a temperature of about 40-70° C. and at a pH value in the range of 3-7. This treatment results in the denaturation of the secondary proteins that are present in the form of traces, and the same are then removed by filtering after the cooled solution, which is preferably cooled to a temperature of about 0-5° C. by being left in a refrigerator for 24 hours, is removed from the refrigerator.

This heating method either taken alone, or in combination with a dialysis method in which the lysozyme solution is dialyzed through a cellophane membrane against distilled water results in the production of a lysozyme solution which can be safely administered parenterally, either intramuscularly or intravenously.

The following examples are given to illustrate the method of production of the lysozyme solutions free of secondary side effects, the scope of the invention not, however, being limited by the details of the examples.

EXAMPLE 1

An aqueous solution with lysozyme content of about 10%, and pH-values in the range of about 7 after a heat treatment at a temperature of 70° C. and cooling to 0° C. and filtering is placed in a cellophane membrane against distilled water, and stirred for several hours. The aqueous solutions containing the lysozyme passed through the membrane are put together and the lysozyme is separated by vacuum evaporation, or by salting, or finally, by flowing across carboxyl resin IRC 50, previously treated with a phosphate buffer 0.2 M and a pH=7.18, and eluting then with a salt solution.

EXAMPLE 2

An aqueous solution with lysozyme contents of 2% and a pH-value of 3, is heated at a temperature of 40° C. After cooling, the solution is left overnight in a refrigerator, at a temperature in the range of 0°-5° C. The

solution is then filtered, and the lysozyme separated as in the Example 1.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. Method of relieving the pain of a patient suffering from cancer, which comprises injecting such patient with lysozyme which is free of proteinaceous impurities.

2. Method of relieving the pain of a patient suffering from cancer, which comprises injecting such patient with a sterile aqueous solution of lysozyme which is free of proteinaceous impurities.

3. Method of relieving the pain of a patient suffering from cancer, which comprises injecting such patient with a sterile aqueous retard-solvent solution of lysozyme which is free of proteinaceous impurities.

4. Method of relieving the pain of a patient suffering from cancer, which comprises injecting such patient with a sterile aqueous polyvinylpyrrolidone solution of lysozyme which is free of proteinaceous impurities.

5. Method of relieving the pain of a patient suffering from cancer, which comprises intramuscularly injecting such patient with lysozyme which has been previously freed of proteinaceous impurities.

6. Method of relieving the pain of a patient suffering from cancer, which comprises intravenously injecting such patient with lysozyme which has been previously freed of proteinaceous impurities.

7. Method of relieving the pain of a patient suffering from cancer, which comprises injecting such patient with lysozyme which is free of proteinaceous impurities in a daily dose of 125 to 500 mg.

8. Method of relieving the pain of a patient suffering from cancer, which comprises parenterally injecting such patient with a sterile aqueous preparation of purified lysozyme, prepared by heating at about 40-70° C. an impure aqueous 2-10% lysozyme-containing, proteinaceous solution, having a pH value of 3-7, to denature undesired proteinaceous impurities; cooling the solution at a temperature of about 0-5° C.; filtering the thus cooled solution so as to separate the denatured proteins therefrom; and incorporating the purified lysozyme thereby obtained into an aqueous parenteral solution.

9. Method of relieving the pain of a patient suffering from cancer, which comprises parenterally injecting such patient with a sterile aqueous preparation of purified lysozyme, prepared by heating at about 40-70° C. an impure aqueous 2-10% lysozyme-containing, proteinaceous solution, having a pH value of 3-7, to denature undesired proteinaceous impurities; cooling the solution at a temperature of about 0-5° C.; filtering the thus cooled solution so as to separate the denatured proteins therefrom; dialyzing the aqueous solution containing the purified lysozyme through a dialysis membrane against distilled water; and incorporating the purified lysozyme thereby obtained into an aqueous parenteral solution.

10. Method of relieving the pain of a patient suffering from cancer, which comprises parenterally injecting such patient with a sterile aqueous prolonged-action polyvinylpyrrolidone-containing parenteral solution of purified lysozyme, prepared by heating at about 40-70° C. an impure aqueous 2-10% lysozyme-containing, proteinaceous solution, having a pH value of 3-7, to denature undesired proteinaceous impurities; cooling the solution at a temperature of about 0-5° C.; filtering the thus cooled solution so as to separate the denatured proteins therefrom; dialyzing the aqueous solution containing the purified lysozyme through a dialysis membrane against distilled water; and incorporating the purified lysozyme thereby obtained into an aqueous prolonged-action polyvinylpyrrolidone-containing parenteral solution.
